UNITED STATES PATENT OFFICE.

HERMANN ROMÜNDER, OF MISHAWAKA, INDIANA.

TRUNK.

1,015,511.

Specification of Letters Patent.

Patented Jan. 23, 1912.

Application filed December 28, 1908. Serial No. 469,514.

To all whom it may concern:

Be it known that I, HERMANN ROMÜNDER, of Mishawaka, Indiana, have invented a Trunk, of which the following is a specification.

This invention relates to trunks, valises, packing-cases, and other boxes and packages, and has for its object to provide such articles of strong and durable character, im-
10 pervious to moisture without requiring any additional covering, and which shall combine lightness of weight and simplicity and cheapness of construction with unusual strength and durability.

15 More particularly I aim to provide an improved construction of the trunk described and claimed in my former United States Patent No. 774,921, dated November 15, 1904, in which is shown a trunk or box
20 made up of compound veneer-plates and provided with rounded corners and paneled sides.

The trunk referred to, while it represented an advance in the art showed, on being subjected to long and severe testing, certain weak points, which by the present construction I aim to eliminate. In my former construction I showed how a trunk could be constructed with all twelve of its edges and
30 all eight of its corners rounded. Such construction, when the elements of which the trunk is built are secured firmly together so that they cannot be separated, as by bending or shock, offers great advantages in the
35 manner of strength, because of the manner in which baggage is customarily handled at railroad stations. As well known, in the handling of baggage by railway-employees, porters and others, trunks are subjected to
40 impact, shock and wear almost entirely upon their corners and edges, more particularly the end-edges, and they are usually skidded along floors and platforms upon their end-edges, which, therefore, take nearly all the
45 wear. In the square-edged construction, the body of the trunk is rigid, and such jars and impacts upon the edges and corners act violently to loosen up the nails and rivets which hold the boards or planks making up
50 the trunk together, as well as the metal corner pieces, which protect the wood against splintering. In the round-edged construction, on the contrary, the shock comes upon a flat surface having some yield or give to
55 it, so that the impact is taken up by the

yielding of the edge-pieces, especially so when, as in my construction, they are made of more or less flexible compound veneer; hence when the elements are fastened together sufficiently securely to prevent their
60 being separated by mutual bending, there is no danger of their becoming separated by impact.

The particular defect of my construction described in the aforesaid patent I have found to be in the loosening of the metal cap-plates at the corners, the reason for and manner of avoiding which were not entirely obvious; but by a series of prolonged tests I have discovered that this is due to
65 impact upon the edge of the trunk beyond the metal corner-pieces, which because of the flexibility of the round edge-plate causes it to bend or yield as aforesaid, while the metal corner-piece has no such yielding
70 quality, and therefore the rivets holding it in place necessarily become loosened. This is the particular defect which I seek in my present construction to eliminate. Furthermore, I aim to provide recessive edges, that
75 is to say, edge-pieces, which lie below instead of standing flush with the edges of the side-pieces, the latter being brought so close to the edges of the trunk that they protect the edge-pieces by taking a portion of the
80 shock; especially so when, as in my present construction, I reinforce them by girth-straps, and reinforce the girth-straps by
85 filling-strips between them and the edge-pieces, in a manner which will be described.

90 A further improvement in the present construction rests in the longitudinal bars or straps, which stand out beyond the surface of the side and edge-pieces sufficiently to absolutely prevent under any ordinary circumstances the impact falling directly upon the side or edge-pieces; and in the manner in which the elbows of said longitudinal bars are provided with metallic runners on which the trunk may be easily and
95 safely skidded, and which prevent indentation, splintering and breakage of the bars themselves.

100 A further improvement in my present construction is the interlocking of the corner-pieces or cap-plates with the longitudinal bars and girth-straps in such a manner that it is practically impossible to subject the edge-pieces to shock or impact near the
105 corners except as the impact is transmitted
110

through the said cap-plates. To accomplish this, the metal cap-plate is also given a special shape, acting in conjunction with the girth-straps and longitudinal bars to 5 shield the edge-pieces at the corners.

My invention comprises the aforesaid arrangement of side and edge-plates, girth-straps, filling-strips, longitudinal bars, runner and corner cap-plates, all as will be 10 hereinafter more particularly described and pointed out in the claims.

For the better understanding of my invention I have described below the most improved form thereof, reference being had 15 to the accompanying drawings, wherein,

Figures 1, 2 and 3 are respectively a perspective view, a plan and a front elevation of the most improved form of my invention; and Figs. 4, 5, 6 and 7 are transverse sections through the edges and corners taken 20 respectively on the lines 4, 5, 6 and 7 of Fig. 2.

In these drawings every reference letter and numeral refers always to the same part.

25 The trunk as shown comprises a body A and a cover B hinged thereto at one edge in any preferred manner, as by hinges C, and having fastening means such as a lock D, clips E, and tangs F at the opposite side.

30 At the sides may be arranged handle-straps G and guide-tangs H. These devices are, however, optional, and have no relevancy to the improvements here claimed. The trunk-body A and cover or lid B are substantially 35 alike in construction except that one is deeper than the other, therefore it will be enough to describe the latter one. It is made up of top-plate b' of suitable material such as three-ply veneer, and four side-plates b² 40 of the same material, and the edges are closed by means of curved edge-plates b³ of quadrantal section, as shown in the sectional views Figs. 3, 4 and 5, said edge-plates underlying the edges of the plates b' and b².

45 Each pair of side-plates b² are united together at their ends by quadrantly curved edge-plates b¹⁰, which underlie the edges of the plates b². The overlapping edges of all the plates are firmly 50 secured together by a special gluing process, (forming no part of this invention), which constitutes them substantially a simple integral piece and renders rivets unnecessary for holding these parts together.

55 Transversely of the cover, to wit, from front to rear thereof, run the reinforcing or girth-straps b⁴, which I prefer to make also of compound veneer, and which are secured to the plates b¹, b² and b³ at proper intervals by means of rivets b⁵. Where each girth-strap b⁴ passes around the edges, it will be observed that owing to the depression of the edge-plates below the top of the side-plates, there is an open space which can be 60 filled by a filling-strip b⁶, which is specially

advantageous because it admits of an extra reinforcing thickness at this particular point where it is most needed, without unduly overweighting the trunk with material which is not needed.

70 The longitudinal reinforcement is further provided in the shape of a pair of bars b⁷ which run lengthwise along the front and back edges of the plate b¹. These bars where they turn over the end-edges are provided with reinforcements b⁸, which I shall term runners, for the reason that they serve for skidding the trunk smoothly along the floor or platform in the manner customary among baggage-handlers. It will be observed 75 that the runners b⁸ are curved or convexed both longitudinally and transversely, as shown in the sections, Figs. 6 and 7, whereby they are rendered extremely strong, and, besides completely cover the wood of the bars b⁷ at 80 this point, effectually preventing the splintering or denting thereof by impact. Between the elbows of the bars b⁷ and the underlying surface of the plates b³ are also inserted reinforcing filling-strips b⁶, in the same manner as under the girth-straps. Where the bars b⁷ cross the girth-straps b⁴, they are notched or mortised, as shown at b⁹, to permit both elements to lie 85 flush upon the surface of the plate b¹. 95

The construction of the corners according to my present invention is very different from that of my aforesaid patent, and is a very great improvement thereover. The corners are covered by a metal cap-plate I, 100 which I prefer to make of drawn steel and of special shape which gives it both strength and resiliency. In the center it is provided with a raised boss or teat i², surrounding which is a depressed annular rib, i¹, the 105 effect of which is to give the cap-plate a certain resiliency against shock while being at the same time very resistant against permanent deformation. Now it will be observed that this cap-plate is not merely riveted onto the inclosing plates, b¹, b², b³ and b¹⁰, as in my former construction; but the end-girth-straps b⁴ and longitudinal bars b⁷, which lie along the edges of the top-plate b¹, 110 overlap the edges of the cap-plate I, and are 115 riveted to the plates b¹, b², b³ and b¹⁰ through the metal of the cap-plate, which, therefore, is inclosed between them; as well as two filling-strips b⁶, and a third filling-strip, b¹¹, which provide a double thickness on the 120 edge of the plate at the point of riveting. In addition to this, a raised quadrantal rib, i², is formed on the horizontal side of the cap-plate I, and is complementary to the runner b⁸ and to the elbow of the girth-strap b⁴ in forming a projection beyond the edge-pieces of the trunk (b¹⁰ and a¹⁰). A 125 consideration of this construction will show that thereby the corners are trebly and quadruply reinforced (especially on the sides 130

protected by the runners b^8), so that it becomes practically impossible to detach or loosen the cap-plates. Moreover, each of the three sets of edges is protected in several ways against receiving any shock; the longitudinal edges by the girth-straps b^4 and filling-strips b^6 ; the horizontal end-edges by the runners b^8 , bars b^7 , and fillers b^6 ; and the vertical end-edges by the projecting ribs i^8 and filling-strips a^{11} and b^{11} . In addition, the edge-pieces are protected by their being depressed below the side, top and bottom-pieces; the longitudinal edges by the bars b^7 , which lie along their margins; the horizontal end-edges in a similar manner by the end girth-straps b^4 ; and the vertical end-edges by both the longitudinal bars and end girth-straps, which lie on opposite sides of the edge-plates a^{10} , which, therefore, are depressed on all sides below them, and there is no possibility of a blow directly on the edge-plates except from a projecting point, corner or pointed instrument. It will be seen that these various reinforcements, by projecting beyond the various edge-plates in various ways, practically shield them not only against ordinary flat floors but against such things as projecting nails or uneven surfaces. Hence the body of the trunk itself does not easily become marred or broken in transportation. At the same time the resilience and lightness of the trunk are preserved in every particular.

As the body of the trunk is constructed in exactly the same manner as the lid, the parts a^1 to a^{11} , which correspond in number to the parts b^1 to b^{11} , need not be individually described.

At the edges of the lid and body the plates b^{11} overlie the edges of the plates a^{10} , extending down slightly farther than the latter, so as to form in effect a rabbet or mortise-joint, and in like manner the side-plates b^2 of the lid may overlap corresponding plates (not here shown), on the inside of the side-plates a^2 of the body.

Various changes and modifications in the constructions as herein shown may be made without departing from the spirit of my invention, and I wish it understood therefore that the latter is not otherwise limited than by the reasonable scope of my claims.

Having thus described my invention, what I claim as new and desire to secure by Letters Patent is:

1. In a trunk or box, a member which may be a lid or body comprising a middle-plate, four side-plates, four quadrantly curved edge-plates underlapping said middle and side-plates and united thereto, a plurality of transverse girth-straps extending across said middle, side and edge-plates and united thereto, and a plurality of longitudinal bars extending across said middle, side, and edge-plates and united

thereto, said longitudinal bars being deeper than said transverse straps and recessed at the points where they cross the latter whereby they are adapted to lie upon the surface of the middle-plate; filling-strips underlying said girth-straps and bars between them and said edge-plates, and convex cap-plates filling the open spaces at the four corners. 70

2. In a trunk or box, the corner-construction comprising, in conjunction with the three quadrantly rounded edge-plates which meet at the corner and form the box-edges and have their ends truncated so as to leave an open space at the corner-angle, a corner cap-plate closing said open space, 80 and two reinforcing members at right angles passing around adjacent edges of the trunk or box and secured to said edge-plates, the edges of said cap-plate lying between said reinforcing members and said 85 edge-plates.

3. In a trunk or box, the corner-construction comprising, in conjunction with the three quadrantly rounded edge-plates which meet at the corner and form the box-edges and have their ends truncated so as to leave an open space at the corner-edge, a corner cap-plate closing said open space, 90 and two reinforcing members at right angles passing around adjacent edges of the trunk or box and secured to said edge-plates, the edges of said cap-plate lying between said reinforcing members and said 95 edge-plates; the said cap-plate having a raised quadrantal rib opposite the angle between the said reinforcing members and complementary to the latter. 100

4. The construction for a trunk which comprises, in combination with a trunk-body having rounded edges, projecting corner pieces at the ends of such edges, and reinforcing and protecting members in the form of straps or bars lying parallel with said edges at the sides thereof and projecting beyond said edges, so that said 110 edges are substantially shielded on all sides by projecting parts. 105

5. A construction for a round-edged trunk which comprises, in combination with side-plates, top or bottom-plate, and quadrantly rounded edge-plates, secured together and leaving an open space at the corners, a spherical-octant-shaped corner-cap-plate covering said open space, and having a raised rib on one side of the octant, in combination with reinforcing members covering the edges of the other two sides of the octant and secured to said top and edge-plates through the material of said cap-plate. 115 120 125

6. A construction for a round-edged trunk which comprises, in combination with side-plates, top- or bottom-plate, and quadrantly rounded edge-plates, secured together and leaving an open space at the 130

corners, a spherical-octant-shaped corner-cap-plate covering said open space, and having a raised rib on one side of the octant, in combination with reinforcing members covering the edges of the other two sides of the octant and secured to said top and edge-plates through the material of said cap-plate; the reinforcing member on the horizontal end-edge of the trunk being

provided with a quadrantal metal elbow of 10 U-shaped cross-section.

In witness whereof I have hereunto set my hand this 25th day of December, 1908.

HERMANN ROMÜNDER.
